UNITED STATES PATENT OFFICE.

FRANCIS A. RICHARDS, OF MUSCATINE, IOWA.

AUTOMATIC FURNACE-REGULATOR.

1,123,009.

Specification of Letters Patent. Patented Dec. 29, 1914.

Application filed June 4, 1914. Serial No. 843,032.

To all whom it may concern:

Be it known that I, FRANCIS A. RICHARDS, a citizen of the United States, residing at Muscatine, in the county of Muscatine and State of Iowa, have invented certain new and useful Improvements in Automatic Furnace-Regulators, of which the following is a specification, reference being had to the accompanying drawings.

10 This invention relates to an improved automatic furnace regulating apparatus, and has for its primary object to provide a reliable and efficient electrically controlled means for automatically operating the direct draft and check draft dampers of the furnace by the increase or decrease of the temperature in a room or apartment to a predetermined degree.

In its more specific aspect, the particular 20 object of the invention resides in the provision of a drum, the shaft of which is provided at its ends with crank arms, chains connected to said arms and to the respective furnace dampers, a weighted cable attached 25 at one of its ends to said drum, a pivoted lever to which the other end of the cable is attached, and an electrically actuated keeper member coöperating with said lever to hold the drum against rotation.

30 The invention has for still another object to produce a device of the above character for automatically operating the dampers of a hot-air, hot-water, or similar furnace, which is exceedingly simple in its construction, and may be installed at comparatively 35 small cost.

With the above and other objects in view, the invention consists in novel features of construction, combination, and arrangement 40 of parts as will be hereinafter referred to and more particularly pointed out in the specification and claims.

For a full understanding of the invention, reference is to be had to the following description and accompanying drawings, in which—

Figure 1 is a side elevation illustrating the preferred embodiment of my invention, the operating circuit therefor being shown in diagram; Fig. 2 is a similar view showing the latch lever in its released position; Fig. 3 is a section taken on the line 3—3 of Fig. 1; Fig. 4 is a section taken on the line 4—4 of Fig. 1; Fig. 5 is a front elevation of the 55 thermostatic switch; and Fig. 6 is a section taken on the line 6—6 of Fig. 5.

Referring in detail to the drawings, 5 designates a base of suitable insulating material which is secured upon a beam or other stationary support in the furnace room. To 60 the opposite edges of this base at one of its ends the depending bracket plates 6 are secured and in the lower ends of said plates a drum shaft 7 is journaled. This shaft is provided upon its ends with crank arms 8 65 which extend in relatively opposite directions, each of the arms being preferably provided with an extensible tubular section 9. This adjustable arm section may be rigidly secured in its adjusted position by means of a setscrew 10. To the extensible section 9 of each of the crank arms one end of a chain 11 is attached. These chains pass over suitable guide pulleys or sheaves 12 and have their other ends attached to the direct draft 70 damper 13 and the check damper 14 respectively of a furnace. Upon opposite sides of one of the depending bracket plates 6 spring contact strips designated by the numerals 15 and 16 respectively are secured for a purpose to be hereinafter fully pointed out. Upon the shaft 7 a drum 17 is rigidly secured. Upon the insulating base 5 adjacent its opposite end a bracket member 18 is secured and upon the depending arm of said 75 bracket member a pair of electromagnets 19 are mounted, said magnets being connected in series. A latch lever 20 is fulcrumed intermediate its ends upon a bolt 21 mounted in the spaced arms 22 fixed upon the base 80 5. One end of this lever is formed with a downturned lug 23 while to the other end thereof a cross arm 24 is secured. The opposite ends of this arm are adapted to engage stop screws or pins 25 fixed in each end 85 of the drum 17 at diametrically opposite points upon its periphery.

26 indicates a keeper plate which is hinged as at 27 upon the base 5. The other end of this plate is provided with an upwardly projecting obliquely disposed flange or tongue 28. This keeper plate constitutes an armature for the electromagnets 19. The keeper plate is yieldably held against movement by magnetic attraction, when the magnets are energized, by means of a spring 29, said spring maintaining the obliquely inclined tongue or flange 28 of said plate in engagement with the downwardly projecting lug 23 on the end of the lever 20. To 100 the drum 17 one end of the cable 30 is attached, the other end of said cable being 105

connected to the lever 20 at a point between its fulcrum and the lug 23. A wheel or pulley 31 is movably engaged upon said cable, and from this wheel a suitable weight indicated at 32 is suspended.

5 The operating circuit includes a movable thermostatic element 33 which is secured upon a plate 34. One end of this plate is fixed upon a base plate 35 while the other 10 end thereof is disposed between the spaced terminals 36 and 37 respectively. The terminal 36 is mounted upon the base plate 35 and suitably insulated therefrom while the terminal 37 is adjustably mounted upon a bracket arm 38 also insulated from said base plate. One end of a wire 39 is electrically connected to the depending contact strip 15 upon the base 5 while the other end of said wire is connected to a binding post 40 on the 15 base 35 of the thermostat. This binding post is also connected by a wire 41 to the terminal 36.

20 42 designates the battery or other source of electric current, one pole of which is connected by a wire 43 to the binding post 44 on the base 35. A switch lever 45 is mounted upon said binding post and is adapted to be engaged with the head of one of the screws 46 which secure the base 35 upon a 25 wall or other support. A wire 47 is also attached to the other of the contact strips 16 to a binding post 48 on the bracket 38. To the depending plate 6 between the spaced 30 contact strips 15 and 16, one end of a conducting wire 29 is connected, said wire being 35 extended through the insulating base 5 and connected at its other end to the electric magnets 19. A wire is also connected to said magnets and to the other pole of the 40 battery 42.

45 With the several parts in the relative positions shown in Fig. 1 of the drawings, wherein the check draft is open and the direct draft damper closed, when the temperature in the room or apartment reaches a predetermined degree, say 72° , the movable thermostatic element operates to engage the end of the metal plate 34 with the terminal 36. It being understood that the switch lever 45 has been moved into engagement with the head of the screw 46, a circuit will thus 50 be closed from the battery through wire 43, lever 45, the base 35, the switch blade 34, terminal 36, wire 41, binding post 40, wire 39, contact strip 15, arm 8 of the drum shaft, bracket plate 6, wire 49 to the electromagnets, and through wire 50 back to the battery. When the electromagnets are thus 55 energized, the movable keeper plate 26 is attracted against the action of the spring 29, and the gravity movement of the weight 32 unwinds the cable 30 from the drum 17 and causes said drum to rotate. The downward pressure of the lugs 25 upon the end 60 of the lever 20 rocks said lever upon its

fulcrum. As soon as the circuit is broken, the magnets are deenergized and the lugs 25 having moved below the lever 20, said lever is returned to its normal position by the weight 32, the lug 23 on the end of the lever 70 engaging the tongue 28 of the keeper plate 26 and moving said plate to the position shown in Fig. 1. As soon as the crank arm on the end of the drum shaft moves out of engagement with the contact strips 15, the 75 circuit above described is broken and the keeper plate is returned to its normal position by means of the weight 32 suspended from the cable 30. Thus after the drum has made one-half a revolution the stop screws 80 will again engage the arm 24 on the lever while the crank arm on the drum shaft 7 will engage the other of the contact strips 16. In this rotation of the drum, the cable 30 will partly unwind therefrom while the 85 chains 11 will be moved in opposite directions over the guide pulleys 12 and the check draft damper closed while the direct draft damper is opened. When the temperature in the room lowers to the predetermined point, 90 the blade 34 will engage the other of the terminals 37 and the circuit will then be closed from the battery 42 through wire 43, lever 45, the base plate 35, blade 34, terminal pin 37, wire 47, contact strip 16, the crank arm 95 8 of the drum shaft, bracket plate 6, wire 49 to the electromagnets 19, and then through wire 50 and back through the battery. Thus the keeper plate is again moved by the energization of the magnets to release 100 the latch lever 20 so that the drum 17 may rotate for another half revolution, the movement of the respective chains 11 being reversed and the check draft damper closed while the direct draft damper is opened. 105 It will be understood that by simply adjusting the extensible sections 9 of the crank arms, the extent to which the dampers are opened may be regulated as desired.

110 From the foregoing description taken in connection with the accompanying drawing, the construction and manner of operation of my improved automatic furnace regulator will be clearly and fully understood. The cable 30 is of such length and 115 so attached to the drum 17 that when the same is completely unwound from the drum, the crank arm of the drum shaft is out of contact with the plates 15 or 16 and the furnace is practically closed. It will thus 120 be obvious that no further operation of the mechanism can take place, as the operating circuit for actuating the keeper plate can not be closed except through the arm of the drum shaft. It is therefore manifest that 125 all danger of overheating the furnace by the apparatus running down and leaving the direct draft damper in its open position will be obviated.

130 My improved damper operating appara-

tus, while of very simple construction, is highly efficient and reliable in practical operation and relieves the user of the necessity of expending considerable time and attention on the proper operation of the furnace. The apparatus may be satisfactorily employed in connection with either hot-air, hot-water, or steam heating furnaces. In view of the fact that the several elements employed are all of very simple form and construction, it will further be appreciated that the invention can be produced at small manufacturing cost.

While I have above described the preferred form, construction, and arrangement of the several elements employed, it will be understood that the device is, nevertheless, susceptible of considerable modification therein, and I therefore reserve the privilege 20 of resorting to all such legitimate changes as may be fairly embodied within the spirit and scope of the invention as claimed.

What is claimed is:

1. In an automatic furnace regulator, the combination with the furnace dampers, of a drum, oppositely extending crank arms on the ends of the drum shaft, flexible connections between said crank arms and the respective dampers of the furnace, a weight- 30 ed cable attached at one of its ends to said drum, a lever fulcrumed intermediate of its ends, stop pins secured to the periphery of the drum at diametrically opposite points, a movable keeper engaged with one end of said lever and holding the opposite end thereof in the path of said stop pins, the other end of said cable being connected to said lever adjacent to the keeper, electromagnets adapted to move said keeper when 40 energized and release the lever to permit of the rotation of the drum, and a circuit

for said magnets including a thermostatic element adapted to close said circuit upon an increase or decrease in temperature to a predetermined degree, said circuit including spaced contacts with which one of the crank arms upon the drum shaft is adapted to alternately engage. 45

2. In an automatic furnace regulator, the combination with the furnace dampers, of a drum, oppositely extending crank arms on the ends of the drum shaft each provided with an extensible section, flexible connections between said crank arms and the respective dampers of the furnace, a lever 50 fulcrumed intermediate of its ends, stop pins secured in the periphery of the drum at diametrically opposite points with which one end of the lever is adapted to engage to limit the rotation of the drum, said lever 55 being provided with a lug on its other end, a cable attached to the latter end of said lever and to said drum, a weight suspended from said cable, a spring-held keeper plate having a tongue on one end engaged with 60 the lug on said lever, electromagnets adapted when energized to move said keeper and release the lever to permit the same to move out of the path of movement of the stop pins on said drum, an electric circuit for said 65 magnets including a movable thermostatic element adapted to close the circuit upon an increase or decrease in temperature to a predetermined degree, and spaced contact members with which one of the crank arms 70 on the drum shaft is adapted to engage. 75

In testimony whereof I hereunto affix my signature in the presence of two witnesses.

FRANCIS A. RICHARDS.
